UNITED STATES PATENT OFFICE.

JAMES I. ORMSBY, OF JERSEY CITY, NEW JERSEY.

PORTABLE ASH-SIFTER.

1,314,424.

Specification of Letters Patent. Patented Aug. 26, 1919.

Application filed April 6, 1918. Serial No. 227,040.

To all whom it may concern:

Be it known that I, JAMES I. ORMSBY, a citizen of the United States, and a resident of Jersey City, in the county of Hudson and 5 State of New Jersey, have invented a new and Improved Portable Ash-Sifter, of which the following is a full, clear, and exact description.

The object of the invention is to provide a 10 new and improved portable ash sifter arranged to permit of conveniently and quickly sifting ashes without causing any dust to pass into the kitchen, cellar or other room in which the ash sifter is used at the time. 15 Another object is to permit of conveniently removing from the apparatus the separated ashes and the coal or cinders after the sifting operation is completed. Another object is to render the ash sifter exceedingly compact so as to take up very little room, and 20 to allow of readily carrying the ash sifter from one place to another, say from the kitchen to the cellar or vice versa.

With these and other objects in view, the 25 invention consists of certain novel features of construction, as hereinafter shown and described and then specifically pointed out in the claims.

A practical embodiment of the invention 30 is represented in the accompanying drawings forming a part of this specification in which similar characters of reference indicate corresponding parts in all the views.

Figure 1 is a perspective view of the portable ash sifter with the lid of the hinged cover of the casing in open position;

Fig. 2 is a like view of the same with the cover in open position;

Fig. 3 is an enlarged longitudinal central 40 section of the portable ash sifter; and

Fig. 4 is a cross section of the same on the line 4-4 of Fig. 3.

The casing 10 of the ash sifter is open at the top and the open top is adapted to be closed by a box-like cover 11 connected at the rear by hinges 12 to the rear of the casing 10 (see Fig. 4). The front of the cover 11 is adapted to be locked in place by a suitable fastening device 13 such as a hook and 45 stud, as plainly indicated in Figs. 1 and 4. The cover 11 is made box-like and in the form of a shoe blacking box to permit the user to conveniently blacken the shoes whenever it is desired to do so. The cover 11 is 50 provided with a lid 14 connected at its rear by hinges 15 to the top of the cover 11, and the front end of the lid 14 is adapted to be fastened by a fastening device 16 to the cover 11, the fastening device 16 being similar to the fastening device 13 above mentioned. 60

Within the casing 10 is arranged a sifting drum 20 having its top somewhat below the top of the casing 10, and the said sifting drum 20 is mounted loosely on a shaft 21, preferably made tubular, and journaled in 65 suitable bearings in the side walls 22 and 23 of the casing 10. One end 24 of the shaft 21 extends beyond the outer face of the side wall 22 of the casing 10 for the reception of a crank handle 25 provided with a fork 26 70 adapted to straddle a pin 27 extending diametrically through the hollow outer end 24 of the shaft 21 thus permitting the user to conveniently turn the shaft 21.

In order to lock the drum 20 to the shaft 75 21 so as to rotate with the said shaft, use is made of a locking pin 30 removably extending through an aperture 31 in the shaft 21 and engaging a staple 32 arranged on the inner face of the head 33 of the drum 20. 80 On removing the pin 30 from the shaft 21 and staple 32, the shaft 21 can be drawn out through either bearing in the side walls 22, 23, to allow removal of the drum 20 through the open top of the casing for repairs or 85 other purposes. Normally, however, the pin 30 and the staple 32 connect the shaft 21 with the drum 20 to rotate the latter on turning the shaft 21 by the operator correspondingly manipulating the crank handle 90 25. The head 33 of the drum and likewise the other head 34 of the drum are preferably made of wood provided with sheet metal linings 35, 36 at their inner faces, and the rim 37 of the drum is made, preferably, of 95 wire netting and is provided with a removable section 38 to provide an opening through which the ashes to be sifted can be introduced into the drum at the time the said opening is in uppermost position. 100 When this opening is in lowermost position with the section 38 removed then the coal, cinders or the like remaining in the drum 20 after the sifting operation is completed can be discharged from the drum, as hereinafter more fully explained. One end of the removable section 38 of the rim 37 is provided with a pin 40 adapted to engage a staple 41 secured in the peripheral face of the drum head 34, and one end of the said 110 section 38 is adapted to be engaged by a spring catch 42 secured on the head 33 and

serving to lock the section 38 in position on the drum 20. The swinging motion of the spring catch 42 is limited by a screw 43 screwing in the head 33 (see Fig. 3). On 5 disengaging the spring catch 42 from the corresponding end of the section 38 the latter can be shifted sidewise to the right to disengage the pin 40 from the staple 41 thus completely disconnecting the section 38 from the drum for the purpose above mentioned.

In order to lock the drum 20 with the section 38 in either an uppermost or lowermost position, use is made of a locking pin 50 mounted to slide in bearings 51 formed on 15 the outer face of the side wall 22, as plainly illustrated in Figs. 1 and 2. The pin 50 is adapted to pass through a diametrical aperture 52 formed in the outer end 24 of the shaft 21 to hold this shaft against turning 20 at the time the section 38 is either in an uppermost or a lowermost position.

In order to guide the ashes to be sifted into the drum 20 at the time the section 38 is removed and the rim opening is uppermost, use is made of chutes 60 and 61 secured 25 to the front and rear casing walls 62 and 63 of the casing 10 at the upper end thereof, as plainly indicated in Figs. 2 and 4. The chutes 60 and 61 extend inwardly and downwardly and terminate at their lower ends 30 adjacent the rim 37 of the drum 20 at opposite sides of the rim opening so that the ashes can be readily dumped into the drum 20 without danger of any ashes passing down 35 on the outside of the drum. Below the chutes 60 and 61 are arranged annular deflecting plates 65 and 66 secured to the front and rear casing walls 62 and 63 which serve 40 to deflect any dust that arises within the casing during the sifting operation.

In the lower portion of the casing 10 directly above the bottom 70 is arranged a drawer 71 adapted to receive the ashes or the sifted coal from the drum, as hereinafter 45 more fully explained. Guide flanges 72 are secured to the inner faces of the walls of the casing at the bottom portion of the drum 20 to direct the ashes or the sifted coal into the drawer 71. The drawer 71 is preferably 50 made of sheet metal with a head 73 of wood fitting into the drawer opening at the side wall 22 of the casing and this head 73 is provided with a knob 74 adapted to be taken hold of by the operator for sliding the 55 drawer in or out of the casing along its guideways 75 attached to the front and rear walls 62 and 63 of the casing 10 (see Fig. 4). The inner faces of the side walls 22, 23, 62 and 63 of the casing as well as the under side 60 of the bottom of the cover 11 are provided with asbestos linings 80 to prevent the casing from being accidentally charred or ignited by hot coal or cinders. On the shaft 21 are loosely mounted washers 85, 86 extending 65 between the heads 33 and 34 and the

corresponding walls 22 and 23 to prevent binding of the drum on the said walls.

The device is used as follows:

When it is desired to sift the ashes, the cover 11 is swung into open position, as 70 shown in Fig. 2, and then the drum 20 is turned until the removable section 38 is uppermost. The operator now engages the pin 50 with the opening 52 of the shaft 21 to lock the drum in this position. The operator now removes the section 38 as previously described and then dumps the ashes to be sifted into the drum 20 to the rim opening. The operator now replaces the removable section 38 and then closes the cover 11 80 after which the operator disengages the pin 50 from the shaft 21 to permit the operator to rotate the shaft 21 and with it the drum 20 on applying and turning the crank handle 25. On rotating the drum 20 the ashes are 85 separated from the coal and cinders and pass through the meshes of the rim 37 down into the drawer 71. When the sifting operation has been completed the operator removes the drawer 71 and dumps the ashes into an 90 ash can or other suitable receptacle, after which the drawer is replaced. The operator now again opens the cover 11 and turns the drum 20 until the removable section 38 is uppermost, after which the section is 95 removed and the drum is given a half turn to move the rim opening into lowermost position so that the coal and cinders within the drum pass out of the same into the drawer 71 which latter is then removed for dumping 100 the coal and cinders into a coal pail or other receptacle. When this has been done the drawer 71 is returned and the section 38 is replaced on returning the drum to normal position with its opening uppermost.

The ash sifter shown and described is very simple and durable in construction and permits of thoroughly sifting the ashes without danger of any dust arising during the sifting operation passing into the room in which 110 the ash sifter is located. It will also be noticed that the drum 20 can be readily removed from the casing for repairs or other purposes and then replaced for use, as previously mentioned. The ash sifter takes up 115 very little room and is of neat appearance so that when it is not in use it resembles a piece of furniture.

Having thus described my invention, I claim as new and desire to secure by Letters 120 Patent:

An ash sifter, comprising a casing having bearings in two opposing walls below the upper edges of the same, a revoluble sifting drum in the said casing, a drum shaft provided with an aperture and removably mounted in the said casing and on which shaft the said drum is loosely and removably mounted, the shaft being removable through either bearing and having one end extending 13

to the outside of the casing for the application of means for turning the shaft, and a radially disposed locking pin slidable on a head of the drum, the inner end of the pin 5 engaging the aperture of the shaft to lock the drum to the said shaft to rotate the drum on turning the shaft and to allow of removing the shaft from the drum and the casing

and subsequent removal of the drum from the casing, filling means on the shaft between the drum and casing and means on the outer end of the shaft for engaging the outer wall of the casing to prevent inward movement of the shaft and to hold the parts in position.

JAMES I. ORMSBY.
